UNITED STATES PATENT OFFICE.

FRANKLIN R. WHITE, OF WATERBURY, AND LEONARD R. CARLEY, OF WATERTOWN, CONNECTICUT, ASSIGNORS TO THE PATENT BUTTON COMPANY, OF WATERBURY, CONNECTICUT, A CORPORATION OF CONNECTICUT.

FLEXIBLE BUTTON.

Application filed June 20, 1928. Serial No. 286,884.

Our invention relates to new and useful improvements in buttons and more particularly to that kind or type known and referred to as swivel or flexible buttons.

5 The invention in its broadest aspect is similar to the button shown in the patent to L. R. Carley No. 1,191,944 and patented July 25, 1916.

In that construction, however, there was 10 provided an inclosed base or anchor which has been entirely dispensed with in the present invention.

One object of the invention is to provide a button that possesses extreme flexibility and 15 the head of which is capable of a shiftable movement, so that the button-hole, through which the button is to be passed or the wire loop, such as forms the attaching members for the buttons on overalls and similar garments, 20 is prevented from becoming jammed or wedged beneath the hub, which wedging would prevent the button from being readily removed from the button-hole or loop.

Another object of the invention is to provide 25 a flexible button so that it may be telescoped to occupy little space, thus permitting the buttons to pass through a clothes-wringer without injury.

Still another object of the invention is to 30 provide a relatively cheap flexible button that is secured to the material by driving a tack into the button head; this operation being performed in a suitable machine.

As is well known to those skilled in the 35 art, tack buttons are generally applied by placing the buttons in one hopper of a machine and the tacks in another and the fastening machine then operated to quickly drive the respective tacks through the cloth and 40 into the respective button heads in a remarkably rapid manner.

Still another object of the present invention is to so form the top of the eyelet of the button and the bottom of the hub that considerable strength will be added to the button as a whole.

Still another object of the invention is to 45 so construct the button that when the head is moved up on the eyelet, the lower end of the hub will lie in a plane opposite the upper edge of the eyelet, thereby adding strength to the button when the head is tilted or rocked.

Still another object of the invention is to provide a flexible button that will consist 55 of but relatively few parts, may be quickly and readily assembled and easily applied to the goods.

With these and other objects in view, the invention consists in certain new and novel 60 arrangements and combination of parts, as will be hereinafter more fully explained and pointed out in the claims.

Referring now to the drawings showing a preferred embodiment,

Fig. 1 is a plan view of the button, a part 65 being broken away for the sake of clearness,

Fig. 2 is a vertical section with the parts 70 in a normal position,

Fig. 3 is a similar view, but with the parts 75 in extended position and showing a tilted position in dot and dash lines, which it may assume when buttoning and unbuttoning,

Fig. 4 is a detailed section of the eyelet 80 before assembly and before the top edge is spun or pressed over,

Fig. 5 is a detailed section of the anvil,

Fig. 6 is a bottom plan of the same,

Fig. 7 is a detailed section of the button 85 back or shell,

Fig. 8 is a vertical section similar to Fig. 2 of a slightly modified form showing the wall 90 of the eyelet bent inwardly towards the hub and showing a slightly different form of anvil,

Fig. 9 is a similar view to Fig. 8, but with the parts extended,

Fig. 10 is a detailed section of the modified eyelet showing the same in a partly completed condition, and

Fig. 11 is a view of the tack fastener.

Referring now more particularly to the several views and for the present to Fig. 1, there is shown a shell or back 1, which is provided with the hub 2 and a small receiving chamber formed by the outwardly extending portion 3 of the shell and the outer rim 4.

The bottom of the hub has the restricted circular opening 5 and the slightly upwardly 100 extending rim or wall 6, as may be clearly seen in Fig. 7.

Now referring for the moment to Fig. 4, there is seen an eyelet 7, which comprises the upwardly extending hollow hub 8 merging 105 with the lower surface or base 8a of the eyelet,

which in turn again extends upwardly as at 10 and is spun back on itself to form the rim 11.

The hub 8 of this eyelet is first placed 5 through the opening 5 in the shell 1 and the upper edge of the hub 8 then spun over to form the locking rim 9 as may be understood from Figs. 2 and 3.

With the construction as thus far described, 10 it will be seen that the head may telescope or in other words move with relation to the eyelet, but the parts cannot become detached, as the rim 6, when the button is elongated will contact with and be held against separation by the downwardly extending rim 9 of the hub 8.

A construction of this kind allows great 20 flexibility of the head of the button with relation to the eyelet and also allows the head to move away, within certain ranges, from the eyelet, so that the wire loops as used on overalls or garments will not bind when between the button head and eyelet when buttoning or unbuttoning, nor will the goods 25 about the button-hole bind, while at the same time a tilting or flexible movement of the button is provided so that the same may be easily manipulated by the fingers as may be readily understood.

30 When the eyelet and button shell have been so attached an anvil 12 as shown in Figs. 5 and 6 is placed within the shell, as may be understood from Figs. 2 and 3 and this anvil preferably consists of a small hard metal 35 circular plate provided with the hub 13, which is slightly dished as at 14, to cause the point of the tack to bend or crimp in the proper direction.

It might be mentioned at this point that the 40 several views show the parts on a greatly exaggerated scale, for the sake of clearness and the buttons themselves are of the ordinary size used on overalls and other similar garments.

45 This anvil is of relatively hard metal as mentioned and its function is to turn the head of the fastening tack which will shortly be described.

After the anvil is placed within the shell, 50 a cover 15 is placed over the shell and anvil and its peripheral edge bent inwardly to form the flange 16 over the rim 4 of the shell, thus completing the head of the button.

55 It will be noticed that the hub 2 is of slightly less diameter than the inner diameter of the eyelet 7, thus permitting the hub of the button to fit down within the eyelet and to rock or tilt with relation thereto. Also the external diameter of the hub 8 of the eyelet is less 60 than the internal diameter of the opening 5 in the shell.

To secure the button in position, a tack 17 is used and the same is driven through the cloth of the garment 18 up through the hollow hub 65 8 and, its point on striking the dished por-

tion of the anvil, will be mutilated and turned over and extend over the inner edges of the rim 9 of the eyelet, thus tightly securing the eyelet to the cloth and making it impossible for the tack to ever pull out of the 70 eyelet hub or permit the eyelet hub to in any way be pulled away from the cloth 18.

As heretofore mentioned, the tacks and buttons are always applied by a fastening machine which machine drives in the tack 75 with considerable force.

Now referring to the slightly modified form as shown in Figs. 8, 9 and 10, the shell 2' is very similar to the shell 2, but if desired the hub may be slightly less in diameter 80 than the other hub, while the anvil 12' is shown as having a flat bottom surface rather than a dished surface as shown in the preferred form.

It might be mentioned here that either form 85 of anvil might however be used in either the preferred or modified form of button head.

The eyelet 7', however, is different in construction from the eyelet 7, in that the base 8' is turned upwardly and inwardly as at 90 10', rather than outwardly and downwardly as in the preferred form (shown in Fig. 4).

The upper edge of the hollow hub 8' is turned downwardly to form the rim 9', so that this rim when the head is pulled outwardly, will engage with a small rim 6' formed in the hub of the shell 2'.

95 The cooperating parts of the eyelet and the hub are identical with the preferred form and the button head may rock or tilt with relation to the eyelet in the same manner as in the preferred form. The tack 17 is identical with the tack in the former instance and is driven through the cloth and is mutilated when its strikes the anvil, so that the button 100 head and eyelet are fastened to the cloth.

105 By forming the eyelet, however, with the upwardly and inwardly extending rim 10', it will be noticed that when the head is elongated with relation to the eyelet, the lower 110 edge of the hub 2' is in substantially the same plane as the upper edge of the turned over portion 10' of the eyelet.

115 By having the top of this outer rim (when the button is extended) flush with the bottom of the hub of the button head, it will permit a wire loop to slip up and take the strain on the hub of the button and away from the garment. This is also true when used with 120 a button hole instead of a wire loop.

125 From the foregoing it will be seen that we have provided a flexible button that may be easily manipulated by the fingers when being passed through a button hole or when being passed through a wire loop. Furthermore, it not only possesses the advantages of the previous button shown in the patent to Carley, No. 1,191,944, (one of the joint inventors of the present application), but it dispenses with an entire element shown in 130

that button and of course is therefore cheaper to manufacture and assemble. Instead of using the anchor as shown in that invention, it will be noticed that the present anvil is provided with a depending hub which may or may not be dished out on its bottom and this hub projects downwardly in the hub of the button shell, so that the tack when driven in will be deflected in the same manner that the anchor deflects the tack in the patent above referred.

The button head can never be pulled away from the eyelet and the tack of course holds the eyelet tightly to the cloth and when once inserted will never pull away therefrom.

Many slight changes might be made without in any way departing from the spirit and scope of the claims.

Having thus described our invention, what we claim as new and desire to secure by Letters Patent is:—

1. A flexible button comprising an eyelet having a hub open at its both ends, a shell having a hub, the hub of the shell fitting over the hub of the eyelet and free to move along the same and tilt with relation to the eyelet, the hub of the shell and eyelet so rimmed that the parts are held from detachment, an anvil supported by said shell and a cover over said anvil and upper portion of the shell, the hub of the said eyelet adapted to have a fastening member driven therein and the fastening member curled over the rim of said eyelet to thereby secure the same.

2. A flexible button comprising an eyelet having an up-standing hollow open-ended hub, a button head comprising a shell and having a hollow hub adapted to loosely fit over said first mentioned hub and said shell capable of rocking on and moving along the hub of the eyelet, the hub of the eyelet and the hub of the button head both being rimmed to prevent detachment of the two parts, an anvil in said button head supported by said shell and a cover over said anvil, the said anvil adapted to deflect the prong of a fastener and curl the same against the rim of the eyelet to thereby fasten said eyelet to a garment.

3. A flexible button comprising an eyelet having an open passageway there-through, a button head loosely secured to said eyelet, so that the head may move inwardly and outwardly in regard to said eyelet and also rock with relation thereto, an anvil in said button head and supported thereby and a tack adapted to be driven through said eyelet and have its point deflected by said anvil, whereby said eyelet is securely fastened to a garment.

4. A flexible button comprising an eyelet having an open passageway there-through and a button head, said button head so secured to said eyelet, that the head may move to and away from said eyelet and rock with relation thereto and cooperating means on the

button head and eyelet to prevent the parts from becoming detached, a fastener adapted to be driven through said eyelet and into said button head and the end thereof jammed over a portion of said eyelet, to thus secure the 70 eyelet and its button head in its final position.

5. A flexible tack button comprising a shell, an anvil in said shell and a cover over the anvil, said shell having a hub, an eyelet fitting within said shell, said eyelet having an open 75 passage-way there-through, cooperating rims on the shell and the eyelet to prevent detachment of the shell and eyelet and allowing the shell to rock and move with relation to the eyelet, a tack adapted to fit within said eyelet 80 and have its point deflected by said anvil to jam over the rim of the eyelet and thus secure the eyelet and its head to the article to which it is to be attached.

6. A flexible tack button comprising a button head and an eyelet, said eyelet having a central open passage-way there-through, the button head movably and rockably locked to said eyelet, a tack adapted to be forced into said eyelet and jammed against a portion of 90 the button head to thereby jam the tack against the uppermost edge of said eyelet to thereby fasten the eyelet to the material on which it is to be used.

7. A flexible tack button comprising an eyelet having an open passage-way there-through, said eyelet having a hollow hub, the base of the eyelet turned upwardly and inwardly and surrounding said hub, a button heading having an anvil therein and supported by the upper part of the button head, a hub, the hub of the eyelet and the hub of the button head having interlocking rims when the button head is pulled away from said eyelet and the hub of the eyelet adapted to receive a fastening member.

8. A flexible tack button comprising a head having a hub, an eyelet having a central open passage-way there-through having a hub locked within said hub of the button and the button hub capable of a rocking and outward and inward movement with relation to said eyelet, the said eyelet being bent upwardly and inwardly from its base and substantially opposite the bottom of the hub of the button, 115 when the button is in its locked position.

9. A flexible button comprising a button head, an eyelet having an open passage-way there-through and a tack, said button head swivelly and shiftably connected to said eyelet, the tack adapted to be forced into said eyelet and contact with the walls thereof and lock said eyelet rigidly with relation to said tack.

10. A flexible button comprising a shell, an 125 anvil supported in the head of the shell and a cover for said anvil and shell, an eyelet having an open passage-way there-through swivelly mounted within said button head, fastening means adapted to be forced into 130

- said eyelet and deflected by said anvil and contacting with the innermost portion of said eyelet to thereby lock the eyelet with relation to the fastening means.
5. 11. A flexible button comprising an eyelet the eyelet being open at its top and a head capable of sliding along said eyelet and also capable of a rocking movement with relation to said eyelet, cooperating means in the form 10 of integral flanges on the eyelet and button head to prevent detachment of the parts and said eyelet adapted to receive a fastening means to cooperate directly with the said eyelet to thereby secure the several parts together.
12. A flexible button comprising a shell having a hub, an anvil in said shell and having a hub fitting down within the hub of the shell, an eyelet having a hub open at its top 20 and the hub of the shell shiftably mounted on the hub of the eyelet, cooperating locking means on the hub of the shell and eyelet for limiting the movement of the shell with relation to the eyelet, the hub of the eyelet adapted to receive a fastening member and the hub of the anvil adapted to jam the end of the fastening member about the upper edge of the hub of the eyelet.
- 25 13. A flexible tack button comprising a
- button head, an anvil with a hub in said shell 30 and the hub of the anvil being dished on its under portion, an eyelet open at its upper end shiftably connected to said head and the anvil adapted to deflect the prong of a fastener about a portion of the eyelet to secure 35 the eyelet to the article on which it is to be used.
14. In a button, an anvil comprising a plate, a depending hub on said plate and the under portion of the anvil being concaved to a depth 40 less than one-half the thickness of the anvil plate to thereby deflect the prong of a fastener.
15. A flexible button comprising a shell, 45 a cover for said shell, the said shell provided with a hub, an anvil in said shell and the said anvil provided with a hub fitting down within the shell, the said hub having its lower surface concaved, an eyelet rockably secured to the hub of the shell and said anvil adapted to deflect the prong of the fastener over a portion of the eyelet, to secure the eyelet to a garment.

In testimony whereof we affix our signatures.

FRANKLIN R. WHITE.
LEONARD R. CARLEY.
